UNITED STATES PATENT OFFICE.

FRANÇOIS HENNEBIQUE, OF PARIS, FRANCE.

ROAD-BED OF RAILWAY-TRACKS.

1,043,764.

Specification of Letters Patent.

Patented Nov. 5, 1912.

Application filed April 7, 1911. Serial No. 619,582.

To all whom it may concern:

Be it known that I, FRANÇOIS HENNEBIQUE, citizen of the Republic of France, residing at Paris, in the Republic of France, have invented certain new and useful Improvements in Road-Beds of Railway-Tracks, of which the following is a specification.

From the commencement of railways up to the present day the layer of ballast which is interposed between the rail supports and the surface of the ground was considered to sufficiently distribute the loads over the whole of this surface. Today it is known that it is not so, and that the non-agglomerated ballast transmits vertically the pressure of the supports to the surface of the ground without increasing the surface of the latter in contact with the sub-soil.

Under the constant increase in the weight and speed of trains, the deterioration of the tracks has increased very rapidly, exposing the public to the risk of great accidents, in spite of the considerable increase in the work of maintenance, which becomes from day to day more dangerous, troublesome and onerous.

The efforts of engineers have in particular been directed:—1, toward the rails and fish plates, the sections of which have been considerably increased; 2, toward the sleepers, the number of which has been increased until it has rendered the ramming down of the ballast very difficult; 3, to the increase in the thickness of the layer of ballast and the choice of more resistant materials.

Even although on certain much used tracks, the sleepers have been laid sufficiently near together to allow of the surface of the ballast being uniformly and entirely subjected to the pressure, it is everywhere recognized to-day that under the weight of modern locomotives the best protected surfaces become more and more rapidly deformed. Beneath and in contact with the ballast the soil slips laterally, forced out by the weight, or rises and passes through the ballast and appears at the surface between the sleepers, which are forced in, bent and deformed beneath strains which were not foreseen when they were laid and the track packed or rammed. It therefore becomes indispensable to guard against the insufficiency in the resistance of the ground or earthwork in many cases to reinforce it not only as regards the immediate contact of

the loads transmitted thereto by the sleepers and the ballast, but also and more particularly to increase in depth and laterally this augmented resistance which decreases toward the periphery until a superficies is reached which is sufficiently developed for receiving and supporting the loads with a coefficient of security restored to the initial resistance of the natural ground.

Now this invention enables the result hereinbefore considered to be realized, and it consists substantially in the application of vertical ramming to the ground and to the ballast of railway tracks, the strength of which it is desired to increase.

In order to carry out the invention, one or more vertical rammers actuated by any suitable motor and regulated for ramming at suitable distances from the axis of the track, are mounted on a truck. By the aid of these rammers, which are of various weights and diameters according to the nature of the ground and the intensity of the ramming which it is desired to obtain, the layer of ballast is first of all bored between two sleepers, or through the latter, and then the boring having reached the sub-soil, earth more or less mixed with sand, ashes or gravel, is gradually introduced, which is rammed down by means of the corresponding rammer until the resistance of the ground is considered to be sufficient, which may be ascertained by the resistance offered to the entrance of the rammer. It is evident that the quantity of materials introduced and forced into the ground by the rammer creates in this ground a kind of wide base or sole, the resistance of which decreases from the point directly struck by the rammer up to the peripheral extremities where the action of the ramming is weaker, that is to say up to the initial resistance of the ground. When the desired intensity of ramming in the subsoil is attained, a mixture of earth more or less enriched with sand and fine gravel is introduced, in order to cover up the traces of the boring. On packing down the ballast by ramming, there is formed in its interior a body forming a kind of pillar, the base of which has been obtained in the manner hereinbefore explained. In this operation of filling, the ramming as it rises may be greater or smaller according as to whether it is desired to raise the level of the track at the adjacent points, or otherwise.

A way of carrying out the invention is

shown in the accompanying drawings, in which:—

Figure 1 is a plan view of a railway track on sleepers; Fig. 2 is a transverse section; 5 and Fig. 3 is a diagram of the resistance created in the ground as hereinbefore explained.

The ramming holes are indicated by *a*. The approximate form *b* of the ground 10 forced back by the ram is shown in section in Fig. 2.

Of course as many holes may be made and 15 rammings effected as the nature of the ground requires, and the invention is applicable to the reinforcement of any railway track whether laid on transverse or longitudinal sleepers. The resistance of each sole or foot and of its pillar being a function of the force of the rammer in proportion 20 to the section of the latter to the cube of the materials introduced and the number of blows given, the same strength or resistance of the track even in very different

ground may thus be everywhere obtained. The repeated ramming with introduction of 25 ballast materials on reaching near the lower plane of the sleepers causes if necessary, the latter to rise, and this is an excellent means of regulating and correcting depressions in the rails.

I declare that what I claim is:—

The method of reinforcing a roadbed 30 consisting in providing holes in the bed on the sides of the track and intermediate the sleepers and tamping a ballast material in 35 the holes provided to force the material up beneath the sleepers and between the latter.

In witness whereof, I have hereunto signed my name this 21st day of March 1911, in the presence of two subscribing witnesses.

FRANÇOIS HENNEBIQUE.
